(57) **CLAIM**

The ornamental design for the robotic mower wheel, as shown and described.

DESCRIPTION

FIG. 1 is a perspective view of a robotic mower wheel in accordance with an embodiment of the present invention; FIG. 2 is a back view of the robotic mower wheel of FIG. 1; FIG. 3 is a front view of the robotic mower wheel of FIG. 1; FIG. 4 is a left side view of the robotic mower wheel of FIG. 1; FIG. 5 is a right side view of the robotic mower wheel of FIG. 1; FIG. 6 is a top view of the robotic mower wheel of FIG. 1; and, FIG. 7 is a bottom view of the robotic mower wheel of FIG. 1.

The broken lines of the robotic mower wheel in FIGS. 1-7 form no part of the claimed design.
